MANIFOLDING RECORD

Archie M. Bovier, Elmira, N. Y.

Application June 1, 1932, Serial No. 614,689
Renewed November 28, 1934

6 Claims. (Cl. 282—22)

This invention relates to improvements in manifolding record devices and with reference to particular features thereof it relates to a single unitary manifolding assembly or set of record and carbon leaves attached together and being pliable throughout its extent, adapting it for convenient use in connection with typewriters and other forms of writing machines.

It is a general object of the invention to provide an improved manifolding assembly or set of the class mentioned which is of small bulk and pliable throughout its extent, adapting it for use in writing machines and being specially constructed to enable it to be entered into the writing machines quickly and without obstruction and to enable the record and transfer leaves to be very easily and quickly detachable from each other after the inscriptions have been completed.

20 A further object of the invention is to provide a pliable manifolding assembly of the class mentioned wherein the record and transfer leaves are attached together in an improved manner facilitating the separation of the leaves from each other after assembly and at the same time providing an arrangement enabling the leaves to be quickly and easily detached and also providing a structure which is simple in nature and capable of manufacture at relatively low cost.

25 According to another feature of the invention, the record and transfer leaves are bound together in a pliable stub forming a part of the assembly and are provided with transverse severance lines selectively arranged in the different leaves whereby said leaves may be selectively detached from the binding stub quickly and at a single movement. In other words, the weakened severance lines are positioned in some of the leaves while the other leaves are correspondingly unweakened, thus facilitating the selective severance of the leaves from the stub. The severance lines may be thus positioned either in the record leaves or in the transfer leaf or leaves, or they may be partly in the record leaves and partly in the transfer leaves, dependent upon the manner in which it is desired to sever the leaves from the stub.

Another object of the invention is to provide an improved pliable manifolding assembly of the class mentioned having a selective grip arrangement positioned remote from the pliable binding stub with the selectively arranged severance lines whereby the leaves may be selectively gripped in tearing them from the stub.

55 Other objects of the invention will be in part

pointed out in the following detailed description of certain illustrative but preferred embodiments of the invention and will be in part obvious in connection therewith.

The invention accordingly comprises an article of manufacture possessing the features, properties, and the relation of elements which will be exemplified in the article hereinafter described and the scope of the application of which will be indicated in the claims.

For a more complete disclosure and understanding of the nature and objects of the invention, reference is had to the following detailed description and to the accompanying drawing in which:

Fig. 1 is a perspective partially diagrammatic view of a manifolding assembly embodying the invention, parts being broken away for better disclosure;

Fig. 2 is a plan of the assembly of Fig. 1, parts being broken away;

Fig. 3 is a view similar to Fig. 1, showing a slightly modified embodiment of the invention;

Fig. 4 is a plan of the form shown in Fig. 3, and

Fig. 5 is a plan of a further modified embodiment of the invention.

Referring first to the form of the invention shown in Figs. 1 and 2 for a detailed description, the manifolding set shown includes an original record leaf 10, a duplicate record leaf 11 and an interposed transfer leaf 12 positioned to transfer inscriptions made upon the original leaf to the duplicate leaf. For this purpose the transfer leaf is provided with transfer material 13 on its undersurface lying in contact with the record surface of the duplicate leaf 11. While the set shown embodies but two record leaves, additional record and transfer leaves interleaved in the manner shown may be used in case additional copies are required. The record leaves may be provided with any appropriate ruling or blank forms as indicated at 14. It will be observed as clearly seen in Fig. 1 that the original and duplicate record leaves are made from a single integral sheet of paper transversely folded as at 15 to provide the two record leaves in overlapping relation with each other and, as shown, being of substantially the same length. The transverse fold line 15 is preferably weakened in any approved manner as by perforating, thus facilitating severance along this line by exerting a tearing pull. The end of the assembly occupied by the fold line 15 is herein referred to as the top or forward end both of the leaves and of the assembly.

At a short distance to the rearward of the fold

15, the original or record leaf 10 is provided with a transverse weakened severance line 16 preferably disposed parallel to the line 15 and the duplicate leaf 11 is provided with a similar weakened severance line 17, both lines being weakened by perforating, scoring, or by other known means. The severance lines 16 and 17 are spaced only a short distance from the line 15, thus forming two overlapping sections 18 which combine 10 to provide a binding stub for the leaves of the assembly. The transfer leaf 12 is bound into the stub by any appropriate fastening means and either to the upper or lower stub section. It is shown in this embodiment as being attached to 15 the lower stub section by means of a line of adhesive 19. It will thus be seen that the entire assembly including the binding stub portion thereof is pliable throughout its extent and is also very thin and devoid of excess bulk or thickness, 20 whereby it is very well adapted for insertion into writing position in various forms of writing machines including the type of machine using a cylindrical platen. Due to its pliability, the assembly readily conforms to the cylindrical platen 25 surface without wrinkling, or bulging, or assuming other objectionable irregularities. It is to be kept in mind that the disclosure of Fig. 1 and of other figures is partially diagrammatic, the leaves of the assembly being separated some distance 30 from each other in order to disclose the structure satisfactorily. In normal operative position the leaves lie in close contact with each other so that the thickness of the assembly is just about the same as the combined thickness of the constituent leaves.

As shown in Figs. 1 and 2, each of the record leaves 10 and 11 is provided at each longitudinal edge thereof with a weakening or notch opening from the edge into the sheet adjacent to the 40 respective severance lines 16 and 17. This weakening is shown in the form of a small V-shaped starter notch 20, but the notch may be of different form as for example a short slit or cut leading to the edge and extending wholly or partially through the paper. This construction is 45 for the purpose of correctly starting the tearing when the leaves are being detached from the binding stub.

As illustrated in Figs. 1 and 2, it will be noticed 50 that the transfer leaf 12 is unprovided with severance weakening corresponding to the weakened severance lines 16 and 17, this leaf being of its full original strength all the way up to the binding attachment 19 which is shown as disposed 55 between the severance line 17 and the weakened fold line 15. In case it is desired to sever the transfer leaf from the binding and to leave one or more of the record leaves attached thereto, as more fully described below, the transfer leaf 60 may then be provided with a weakened severance line similar to the weakened severance lines 16 and 17. It will thus be noticed that the weakened severance lines are selectively arranged and positioned in the record and transfer leaves for the 65 purpose of facilitating the desired selective severance of the leaves from the assembly. Or, looking at it in another way, severance lines are positioned in selected leaves while other selected leaves are not correspondingly weakened.

In order that the selected leaves, that is, the record leaves 10 and 11 of Figs. 1 and 2, may be 70 conveniently detached from the stub of the assembly after the inscriptions have been made, a selective grip structure for the sheets is provided 75 at a point thereof remote from the binding stub.

This grip device is shown at the bottom or rear end of the assembly, although it may be positioned elsewhere, and includes a thumb notch or depression 21 formed in the end of the transfer leaf 12. Since the record leaves 10 and 12 are not provided with thumb notches corresponding to the notch 21, the corresponding end portions of the record leaves are unlapped by the transfer leaf. It will, therefore, readily be seen that the rear ends of the record leaves may be selectively gripped to the exclusion of the transfer leaf. If the transfer leaf is to be severed from the binding as above suggested, it will be understood that the thumb notch will be formed in the corresponding record leaf and will be omitted from the transfer leaf. In other words, the notches are selectively positioned in the desired selected leaves, while the other leaves are unprovided with such notches.

In use, after an inscription has been completed, 20 the assembly may be gripped at its top end at the binding 18 and at its bottom end in alignment with the thumb notch 21 and a tearing pull exerted to cause severance along the lines 16 and 17. The starter notch is to assure that the 25 tearing will be initiated at the proper points along the respective severance lines. Due to the selective arrangement of the severance lines mentioned, the transfer leaf 12 will remain attached to the stub whereupon it is readily withdrawn 30 from the assembly at the same movement by which the severance is accomplished. Therefore, the record leaves are severed from the assembly and the transfer leaf removed from between them at a single movement. This may be accomplished 35 very quickly and simply and with slight exertion. In case it is desired to remove the original record leaf 10 leaving the carbon and duplicate leaves attached to each other, the original may be 40 thrown forwardly and severed from the stub along the weakened fold line 15. Supplemental data may thereafter be entered upon an overlying record leaf and simultaneously transferred to the 45 duplicate leaf 11. After this the transfer leaf 12 and duplicate 11 may be separated from each other as above described. The folded sheet forming 50 the original and duplicate record leaves provides a protective envelope in which the transfer leaf is enclosed and protected. Also, the attachment or attached margin of the transfer leaf is 55 positioned directly in the fold of the outer sheet and adjacent to the fold line of the latter. In this manner the inner leaf or leaves of the assembly are completely protected during usage.

The modified form of the invention disclosed 60 in Fig. 3 is similar to that of Fig. 1 and corresponding parts are indicated by the same reference numerals with the addition of the index "a". In this embodiment the original leaf 10a is unprovided with a weakened severance line at its top end corresponding to the severance line 16 of Fig. 1, but is attached directly to the stub 18a through the weakened fold line 15a, serving as a 65 detaching line for the leaf 10a.

However, the duplicate leaf 11a is provided with a weakened severance line 17a while the transfer leaf 12a has a corresponding weakened severance line 22 which may, as shown, be in substantial alignment with the line 17a.

For the selective grip formation the original record leaf is provided at its bottom edge with a thumb notch 23 and the leaf 11a is similarly formed with a notch 24 while the transfer leaf 12a is unprovided with a similar notch. This 75

provides a selective grip device whereby the transfer leaf may be gripped to the exclusion of the record leaves and thus selectively severed from its binding along the severance line 22 in 5 a manner above described. If it is desired to first detach the original leaf 10a this may be done by severing it along the line 15a, thus leaving the transfer and duplicate leaves still attached together, but they may be subsequently detached 10 from the stub in the manner above described in connection with Fig. 1.

The embodiment of Fig. 5 is generally similar to the above embodiments and corresponding parts are designated by the same reference numerals with the addition of the index "b". In 15 this, as in the other two embodiments, the original and duplicate leaves are constructed from a single sheet folded along a transverse line which is the line 15b in Fig. 5. In this embodiment 20 the selective severance lines 17b and 22b are arranged as in Figs. 3 and 4, while the original record leaf 10b is correspondingly unweakened and is attached directly to the stub 18b as is 25 done in the embodiment of Fig. 3.

25 For the selective grip device for the form of Fig. 5, the transfer leaf 12b is formed with a thumb notch 25, while the overlying and underlying record leaves are unprovided with corresponding notches and are thus unmutilated at 30 this point. After the inscriptions have been made, the original leaf 10b can be severed along the line 15b, as above described, leaving the carbon leaf attached at the binding stub. The two latter leaves may then be detached from 35 each other as above described.

In each of the different embodiments of the invention it will be noticed that the forward or top end of the assembly is protected by the fold 40 between the two record leaves. This fold forms a protective envelope at the top end of the assembly in which the end of the transfer leaf is received and protected. Thus, the forward end, usually the end introduced into a writing or 45 manifolding machine, is smooth and free from projecting or unprotected edges. The entry of the assembly into such machines is therefore facilitated and the time required for this operation is reduced. This is of importance because the manifolding set of this nature is commonly 50 used for entering records of transactions at different times and it may be necessary to enter each unit into the machine twenty or thirty times before the record or statement is fully completed.

55 It will be understood that the selective grip formations may be formed in various ways other than the illustrative forms above disclosed. For example, the selective grips could be formed by extending portions either of the record or transfer leaves beyond the margins of the other leaves to provide projecting tabs by means of which the leaves could be selectively severed from the stub and separated from each other in the manner 60 above described. If such projecting tabs are utilized either upon the record or carbon leaves, they may be readily detached after serving their purpose by means of weakened severance lines 65 respectively dividing them from the bodies of the leaves.

70 Since the transfer leaves of the different embodiments are ordinarily used but a single time for completing the statement or other entries on the assembly, they are preferably made of thin or tissue paper and the coating of carbon or 75 transfer material on the surface is relatively

thin and light. This helps to keep down the bulk of the assembly as well as the manufacturing cost. The transfer leaves may be discarded when they have served their purpose in the manifolding assembly.

Since certain changes may be made in the above article and different embodiments of the invention could be made without departing from the scope thereof, it is intended that all matter contained in the above description or shown in 10 the accompanying drawing shall be interpreted as illustrative and not in a limiting sense.

Having described my invention, what I claim as new and desire to secure by Letters Patent is:

1. A unitary pliable manifolding assembly including, in combination, a plurality of record leaves and at least one transfer leaf arranged in superposed transfer relation with each other, two of said record leaves including a single sheet 20 folded along a transverse line positioned at the top or forward end of the assembly, and forming an outer envelope within which the transfer leaf is enclosed, said transfer leaf having attachment at a marginal part thereof with said 25 sheet toward the top end of the assembly, the attached margin of said transfer leaf being positioned within the fold of said single sheet and adjacent the fold line of the latter, said record leaves having transverse weakened severance 30 lines spaced inwardly a short distance from said fold line and positioned inwardly beyond said attachment of the transfer leaf and providing between the severance and fold lines a binding 35 stub to which the top end of the transfer leaf 35 is attached, said transfer leaf being unweakened corresponding to the severance lines of the record leaves to facilitate selective severance of the leaves from the stub.

2. A unitary pliable manifolding assembly including, in combination, a plurality of record leaves and at least one transfer leaf arranged in superposed transfer relation with each other, two of said record leaves including a single sheet 40 folded along a transverse line positioned at the top or forward end of the assembly, and forming an outer envelope within which the transfer leaf is enclosed, said transfer leaf having attachment at a marginal part thereof with said 45 sheet toward the top end of the assembly, the attached margin of said transfer leaf being positioned within the fold of said single sheet and adjacent the fold line of the latter, said record leaves having transverse weakened severance 50 lines spaced inwardly a short distance from said fold line and positioned inwardly beyond said attachment of the transfer leaf and providing between the severance and fold lines a binding 55 stub to which the top end of the transfer leaf is attached, said transfer leaf being unweakened corresponding to the severance lines of the record leaves to facilitate selective severance of the leaves from the stub, said record leaves having 60 marginal starter notches leading to the respective severance lines, and a selective grip formation for said assembly remote from said binding stub for facilitating selective gripping of the record leaves.

3. A unitary pliable manifolding assembly including, in combination, a plurality of record leaves and at least one transfer leaf arranged in superposed transfer relation with each other, two of said record leaves including a single sheet 70 folded along a transverse line positioned at the top or forward end of the assembly, and 75

forming an outer envelope within which the transfer leaf is enclosed, said transfer leaf having attachment at a marginal part thereof with said sheet toward the top end of the assembly, 5 the attached margin of said transfer leaf being positioned within the fold of said single sheet and adjacent the fold line of the latter, said record and transfer leaves having one or more weakened severance lines selectively arranged 10 therein near but inwardly of said attachment while a selected leaf or leaves is correspondingly unweakened for facilitating selective severance of certain of said leaves from the assembly, and said single sheet having a weakened transverse 15 severance line positioned substantially at the fold line thereof and outside of said transfer leaf attachment.

4. A unitary pliable manifolding assembly including, in combination, a plurality of record leaves and at least one transfer leaf arranged 20 in superposed transfer relation with each other, two of said record leaves including a single sheet folded along a transverse line positioned at the top or forward end of the assembly, and forming 25 an outer envelope within which the transfer leaf is enclosed, said transfer leaf having attachment at a marginal part thereof with said sheet toward the top end of the assembly, the attached margin of said transfer leaf being positioned 30 within the fold of said single sheet and adjacent the fold line of the latter, said transfer leaf and one of said record leaves having transverse weakened severance lines spaced inwardly a short distance from said fold line and providing 35 between the severance and fold lines a binding stub in which said marginal part of the transfer leaf has its attachment, said single sheet being weakened for severance substantially upon the fold line thereof, and one of the record leaves 40 of said single sheet being unweakened at parts corresponding to said weakened severance lines.

5. A unitary pliable manifolding assembly including, in combination, a plurality of record leaves and at least one transfer leaf arranged in 45 superposed transfer relation with each other, two of said record leaves including a single sheet folded along a transverse line positioned at the top or forward end of the assembly, and forming an outer envelope within which the transfer leaf 50 is enclosed, said transfer leaf having attachment

at a marginal part thereof with said sheet toward the top end of the assembly, the attached margin of said transfer leaf being positioned within the fold of said single sheet and adjacent the fold line of the latter, said transfer leaf 5 and one of said record leaves having transverse weakened severance lines spaced inwardly a short distance from said fold line and providing between the severance and fold lines a binding stub in which said marginal part of the transfer leaf has its attachment, said single sheet being weakened for severance substantially upon the fold line thereof, one of the record leaves of 10 said single sheet being unweakened at parts corresponding to said severance lines, and a selective grip formation for the assembly remote from said binding stub for facilitating selectively gripping said transfer leaf for severance thereof on its severance line from said stub while the record leaves remain attached together. 15

6. A unitary pliable manifolding assembly including, in combination, a plurality of record leaves and at least one transfer leaf arranged in superposed transfer relation with each other, two of said record leaves including a single sheet 25 folded along a transverse line positioned at the top or forward end of the assembly, and forming an outer envelope within which the transfer leaf is enclosed, said transfer leaf having attachment at a marginal part thereof with said sheet toward the top end of the assembly, the attached margin of said transfer leaf being positioned within the fold of said single sheet and adjacent the fold line of the latter, said transfer leaf and one of said record leaves having transverse weakened 30 severance lines spaced inwardly a short distance from said fold line and providing between the severance and fold lines a binding stub in which the top end of the transfer leaf is attached, said single sheet being weakened for severance substantially upon the fold line thereof, one of the record leaves of 35 said single sheet being unweakened at parts corresponding to said severance lines, and a selective grip formation for the assembly remote from said binding stub including a part of the record leaf projecting beyond the adjacent marginal portion of the transfer leaves whereby one of the record leaves may be gripped to the exclusion of the transfer leaf. 40
